UNITED STATES PATENT OFFICE

139,662

DESIGN FOR A CHILD'S PLAY-PEN

Edward Berry, Indianapolis, Ind.

Application August 11, 1944, Serial No. 114,842

Term of patent 7 years

(Cl. D5—5)

To all whom it may concern:

Be it known that I, Edward Berry, a citizen of the United States, residing at Indianapolis, Marion County, Indiana, have invented a new, original, and ornamental Design for a Child's Play-pen, of which the following is a specification, reference being had to the accompanying drawings, forming part thereof.

In the drawings, Fig. 1 is a side elevational view, Fig. 2 is an end elevational view, and Fig. 3 is a perspective view of a child's play-pen showing my new design.

The characteristic feature of my design resides in the ornamental band or panel at the bottom of each of the side walls of the play-pen, as shown.

I claim:

The ornamental design for a child's play-pen, as shown and described.

EDWARD BERRY.
